UNITED STATES PATENT OFFICE.

JULIUS C. GOODWIN, OF PHILADELPHIA, PENNSYLVANIA.

CHAIN-STITCH SEWING-MACHINE.

SPECIFICATION forming part of Letters Patent No. 683,932, dated October 8, 1901.

Application filed October 3, 1900. Serial No. 31,850. (No model.)

To all whom it may concern:

Be it known that I, JULIUS C. GOODWIN, residing at 3137 Euclid avenue, Philadelphia, in the county of Philadelphia and State of Pennsylvania, have invented certain new and useful Improvements in Chain-Stitch Sewing-Machines, of which the following is a specification.

My invention consists of improvements in sewing-machines, and relates especially to that class of sewing-machines known as the "chain-stitch" sewing-machine.

The object of my invention is to construct the looper mechanism in such a manner that the required movements necessary to form the loop of the stitch are accomplished in a simpler and less complicated manner than heretofore.

It is also a further object of my invention to provide a take-up device for the looper-thread.

Referring to the drawings, Figure 1 represents a side view of the sewing-machine, showing the guard-plate in section illustrating my invention. Fig. 2 is a plan view of the looping mechanism. Fig. 3 is a plan view of the looping mechanism, showing the looper in the opposite position from that shown in Fig. 2. Fig. 4 is a vertical section taken on line 4-4, Fig. 2. Fig. 5 is a sectional view on line 5-5, Fig. 1. Fig. 6 is a sectional view on line 6-6, Fig. 1. Fig. 7 is a sectional view on line 7-7, Fig. 4.

Referring to the drawings, A represents the bed-plate of the machine, and A' a standard or upright, having an arm A², in which is mounted in bearings a a the reciprocating needle-rod B, carrying the needle B'. Secured in the standard A' is a shaft C, upon which is fulcrumed the lever C'. The portion C² of said lever is connected by a ball-joint with the eccentric C³ upon the driving-shaft D, from which motion is imparted to said lever C'. The lever C' is also provided with an arm C⁴, which imparts motion to the bell-crank lever C⁵ through the medium of the connecting-rod C⁶. Said bell-crank lever C⁵ is pivoted on the stud-shaft C⁰, secured in the arm A². The outer end of said bell-crank lever is connected, by means of a link b, to the rod B, carrying the needle B', and imparts a reciprocating motion thereto. By

communicating the power to the needle in this manner it will readily be seen that the needle can only have the regular amount of motion, and the length of stroke will not be increased when the machine is running at a high rate of speed, as it does in the construction formerly used, in which a long arm of the lever C' extended between the fulcrum C and the connecting-link b of the needle and which was subject to great variation. With this improved device the length of the arm A² may be increased, which was impossible under the old construction.

In Fig. 5 is shown the manner of mounting the stud-shafts C or C⁰ in the arm A² of the machine. Upon one end of the shaft is formed a cone c, while upon the other end of said shaft is loosely mounted a cone c', which is held in position by means of a set-screw c³. The shaft is permitted to turn in conical bearings formed in the arm A², a projecting boss A³ being provided on one side of said arm for the purpose of making a rigid bearing for the shaft.

In Fig. 6 is shown the manner of constructing the ball-joint between the arm C⁴ and the connecting-rod C⁶. The ball C⁷ is mounted upon the bolt C⁸ and is provided with bosses C⁹, which bear against the bifurcated end of the lever C⁴.

Upon the bed-plate A are provided bearings a' a'. (Clearly shown in Figs. 1 and 4.) Mounted upon a shaft a³, carried by the bearings a' a', is a rocking frame E. Said rocking frame carries a shaft e, to which is pivoted the horizontal frame F, carrying the looper-bar H. Said frame has an arm f, as shown in Figs. 2 and 3, which is connected to the link G. Said link G is pivoted on the shaft g, which is mounted in the bearings a² a² on the bed-plate A. To the link G is attached the connecting-rod g⁴ of an eccentric G' on the driving-shaft D. Said eccentric is adjustably attached to said link by means of the link having an elongated opening g², through which passes the bolt g³ of the eccentric-rod g⁴, thereby permitting the amount of motion of the link G to be readily adjusted.

In the horizontal frame F of the looping mechanism is a sliding bar H, which is permitted to move in the grooves f² of the frame F and is held in position by the plates f³. At

the end of the sliding bar H is provided a lug h, in which is secured the looper I.

Secured to the under side of the sliding bar II is a projection h², having mounted therein 5 a shaft h³, the end of which is spherical and forms a universal joint in the head h⁴ of the connecting-rod h⁵. Said connecting-rod is attached to the arm C⁷ of the lever C' and communicates a reciprocating motion to the looping-bar H, carrying the looper.

A device is provided for taking up the slack thread in the looping mechanism, consisting of a lever J, pivoted at j to the frame F and connected at the point j² with the sliding bar H by means of a connecting-bar j³, which is pivoted to said bar H at the point j⁶. The lever J has a vertical projection j⁴, in which is provided a hole j⁵, through which passes the looping-thread. The essential feature in the construction of this take-up device is the place of pivoting the connecting-bar j³ the lever J. It is necessary that the pivot j² should be situated at a point less than one-half the distance from the fulcrum j to the end of the lever J, thus giving sufficient motion to the outer end of said lever to take up the slack thread when the sliding plate H is withdrawn.

Between the arm f of the frame F and the link G is provided an eccentric-stud G², the construction of which is more clearly shown in Fig. 7 and is used for adjusting the position of the looper in relation to the vertically-reciprocating needle. The end of the link G which receives the eccentric-stud is constructed in the form of a clamp, and by means of the set-screw g' the eccentric-stud can be rigidly held in its proper position.

The operation of the sewing-machine is as follows: Power is applied to the belt-wheel d on the driving-shaft D. On said shaft is an eccentric C³, which communicates power to the lever C', and this lever through the medium of the rod C⁶, the bell-crank lever C⁵, and the link b gives a reciprocating motion to the needle-carrier by the vertical rod B, as above explained. When the needle B' is being raised, the bar H, carrying the looper I, is being moved forward by the arm C⁷ of the lever C', and the looper I passes back of the needle B' and in front of the thread carried by said needle, thus holding the thread to form the first part of the loop. The frame upon which the looping mechanism is carried 50 receives a lateral motion from the shaft D through the eccentric G', as shown in Fig. 4, thus allowing the vertical needle B' to descend back of the looper I, completing the

stitch. The looper I is then withdrawn to the position shown in Fig. 3, the take-up device drawing the slack thread through the guide f⁴ as the needle B' is withdrawn. The feed mechanism K (shown in Fig. 1) is operated by the eccentric L and the cam M, operated by the shaft D in the usual manner. 65

Having thus described my invention, I claim and desire to secure by Letters Patent—

1. In a sewing-machine, the combination of a looper mechanism, a driving-shaft, a rocking frame pivoted on a shaft mounted in bearings on the bed-plate of the machine, a horizontal frame for carrying the looper-bar, a shaft carried by the rocking frame, on which said horizontal frame is pivoted, a link, an adjustable connection between said link and the horizontal frame, shaft and bearings on which said link is pivoted and an eccentric on the driving-shaft for operating the same, substantially as described. 80

2. In a sewing-machine, the combination in a looper mechanism, of a horizontal frame, a take-up device consisting of a lever pivoted to the horizontal frame, projection on said lever, aperture in said projection through which passes the looper-thread, connecting-link pivoted at one end to the lever at a point less than one-half the distance from the fulcrum to the end of said lever, said link pivoted at its opposite end to the sliding looper-bar and a loop f⁴ secured to the frame for guiding the thread, substantially as described. 85

3. In a sewing-machine, the combination in a looper mechanism, of a driving-shaft, a rocking frame, a horizontal frame, a reciprocating bar, grooves in said horizontal frame in which said bar slides, plates secured to said horizontal frame to hold the bar in place, and a projection on said bar adapted to receive the looper substantially as described. 95

4. In a sewing-machine, the combination in a looper mechanism, of a rocking frame, a horizontal frame, an eccentric-stud mounted between said horizontal frame and the link for adjusting the position of the looper, a link carrying said eccentric-stud, a clamp formed in said link for clamping said eccentric-stud, adjustable connection between said link and the eccentric on the driving-shaft, substantially as described. 105

In testimony whereof I have affixed my signature in presence of two witnesses.

JULIUS C. GOODWIN.
